UNITED STATES PATENT OFFICE.

JOHN F. NICHOLS, OF CROMPTON, RHODE ISLAND, ASSIGNOR TO CROMPTON COMPANY,
OF CROMPTON, RHODE ISLAND, A CORPORATION OF RHODE ISLAND.

DESIGN FOR A PILE FABRIC.

Application filed August 6, 1926. Serial No. 18,612. Term of patent 3½ years.

To all whom it may concern:

Be it known that JOHN F. NICHOLS, a citizen of the United States, residing at Crompton, in the county of Kent and State of Rhode Island, has invented a certain new, original, and ornamental Design for Pile Fabrics, of which the following is a specification, reference being had to the accompanying drawing, forming part thereof.

The figure is a plan view of a portion of a pile fabric embodying my design.

I claim:

The ornamental design for a pile fabric substantially as shown.

In testimony whereof I affix my signature.

JOHN F. NICHOLS.
